T. WEYMERSKIRCH

APPARATUS FOR MAKING RAILWAY SLEEPERS

Filed Dec. 14, 1923

Inventor
T. Weymerskirch
By Marks & Clerk, *attys.*

UNITED STATES PATENT OFFICE.

THEODOR WEYMERSKIRCH, OF DIFFERDANGE, LUXEMBURG.

APPARATUS FOR MAKING RAILWAY SLEEPERS.

Application filed December 14, 1923. Serial No. 680,748.

To all whom it may concern:

Be it known that I, THEODOR WEYMERSKIRCH, engineer, a subject of the Grand Duchess of Luxemburg, residing at Differdange, Grand Duchy of Luxemburg, Rue de l'Acier (no number), have invented certain new and useful Improvement in Apparatus for Making Railway Sleepers, of which the following is a specification.

10 The present invention relates to a process of manufacturing iron sleepers, whereof the downward bent edges of the holes are, with a view of reinforcement, flanged in a second operation and then upset.

15 It has been found, in the manufacture of iron sleepers, that it is unsatisfactory to stamp the holes out, whether hot or cold, because the fibers of the laminated metal are cut through and the sleeper is weakened at the points receiving the greatest stress. Owing to the continuously changing working stress, the edges of the holes are torn, more especially at the corners and the sleeper becomes unserviceable.

20 25 It has been proposed to eliminate this drawback by bending the borders of the holes downward like a collar instead of stamping them out. But this does not prevent the formation of rents because the fibers of the laminated metal remained unprotected against the pulling stresses.

According to the present invention, the downward bent edges of the holes are flanged in a second operation and then upset. In this way, the sleeper is considerably strengthened at the rail seat and the possibility of breaking of the edges of the holes therein minimized.

In the accompanying drawing—

40 Fig. 1 shows the working method diagrammatically.

Figs. 2 and 3 show on an enlarged scale, sections through the punching tools before and after the operation.

45 Fig. 4 is a section through the flanging tool.

Figs. 5 and 6 are sectional and plan views, respectively, of the sleeper.

The rolled bar coming from the rolling mill is cut, in the well known way, to the necessary length and is fed by means of a lifting device *a* (Fig. 1) to a flanging machine *b* where it is flanged. The sleepers are then heated in a furnace *c* to a uniform temperature, in order to assure the exact

distances of the holes to be punched in accordance with the gauge of the track.

From the furnace *c*, the sleepers travel into a press *d* where the necessary number of holes is punched therein. The tools of the press are regulated exactly to the temperature the sleeper has received in the furnace so that, after complete cooling of the sleeper, the distance between the holes will be exactly that of a track-gauge.

65 The punching tools mounted on the ram of the press *d* (Figs. 2 and 3) consist of a punching and flanging mandrel *f*, the flanging female die *g* and the snap head die *h*. The sleeper *t* having been placed by means 70 of the lifting device *a* on the table of the press *d*, the ram *e* goes down with the punching- and flanging mandrel *f* on the piece to be worked and cuts it open at the places where the holes are to be produced, as shown 75 in dotted lines in Fig. 2. Up to then the snap head die *h* has served as anvil, in order to prevent the material to be worked from being torn.

80 The snap head die *h* now moves downward, at a somewhat greater speed than the ram, so that the mandrel *f* may move to the position shown in Fig. 3. The mandrel *f* continuing to move downward, the cleft wings *j* are bent into the female die *g* and 85 the opening is thus produced in the sleeper for the tenons of bearing plates or for the clip bolts.

85 The snap head die *h* is provided with a hole *n* enabling the point of the mandrel *f* 90 to completely pierce the sleeper. Material eventually falling off, during the operation, may fall through the hole *u* and the groove *v* of the wedge *k*. This wedge *k* may also be replaced by any other suitable device, for 95 instance eccentrics, cam discs and the like.

During the subsequent upward movement of the ram *e*, the snap head die *h* also raises under the action of the wedge *k* and pushes out of the female die *g* the edges of the holes *j* which have been pressed out; the sleeper *t* is lifted, carried by the lifting device *a* off the press-table *i* (Fig. 1) and placed into the tipping device *l*, ahead of it. This tipping device turns the sleeper 100 through 180° so as to invert it.

105 At the next stroke of the lifting device *a* the sleeper is placed on the table *m* of the press *n*. While the ram *o* to which are fixed the pressing and the flanging 110

tools (Fig. 4) moves downward, the mandrel *p*, the dimensions of which correspond exactly with the desired transversal section of the holes, enters the aperture and 5 the presser plate *q* presses the edges *j* of the holes down into the position *r*.

The mandrel *p* acts in this case as a gauge guided exactly by the female die. The mandrel *p* and the presser plate *q* as 10 well as the female die *s* are mounted on their saddles, in the axis of the sleeper, so as to be able to move to and fro for a few millimeters, so that the distance between the holes of the sleepers may not 15 be altered by a too rigid connection of the flanging tools. On the contrary, the tools will adapt themselves automatically to the predetermined distances of the holes. Simultaneously with the flanging, the sleeper *t* receives, by means of dressing tools 20 mounted on the ram *o*, a slight pressure over its whole length, so that parts that might have been bent are straightened. The sleeper which is now finished is then lifted 25 in the known manner off the table *m*, by means of the lifting device and placed on an automatic conveyer of any known construction. This conveyer carries the sleepers to the stock yard or, if they are to be 30 tarred into a tarring-bath. The supports for the sleepers, on their way between the flanging machine *b* and the press *n* have preferably a shape corresponding to that 35 of the sleepers or they are shifted exactly in the same way by a shifting device in order to assure the exact position of the sleepers after each stroke and thus avoids wrong positions.

Of course, the pressing out, according to 40 Figs. 2 and 3 could just as well be carried out simultaneously with the flanging

of the extremities of the sleepers, but this would be prejudicial to the exactness of the punching.

The whole process requires but little attendance because all the movements are carried out automatically by the movements of the ram of the press or forcibly by a separate driving gear. Owing to the simplicity and to the solidity of the tools, disturbances are rather out of question. The product is a first class one all the operations being carried out at a warm temperature.

The invention is also applicable to all important iron buildings such as bridges, 55 overhead cranes, halls and so on where, for the sake of security, the holes for the rivets and screws may not be pressed out but only drilled. The bending or flanging of the edges of the holes, while the pieces 60 are warm, also results in a more resistant material than pieces with drilled holes and the holes produced according to the present invention will resist the greatest stresses.

Having now fully described my invention, what I claim and desire to secure by Letter Patent is:

In an apparatus of the character described, a device for forming openings in articles, a device for upsetting the edges 70 of the openings, said devices being spaced apart, and means intermediate the devices for receiving articles operated upon by the first device and inverting them for delivery 75 to the second device.

In testimony whereof I affix my signature in presence of two witnesses.

THEODOR WEYMERSKIRCH.

Witnesses:
